(Cl. D34—15)

To all whom it may concern:

Be it known that I, Charles G. Jansky, a citizen of the United States, residing at Chicago, in the county of Cook and State of Illinois, residing at 346 Robinson Road, Riverside, Illinois, have invented a new, original, and ornamental Design for a Figure Toy, of which the following is a specification, reference being had to the accompanying drawing forming a part thereof.

In the drawing,
Fig. 1 is a front perspective view of a figure toy showing my new design; and
Fig. 2 is a front elevational view thereof.

I claim:

The ornamental design for a figure toy, as shown.

CHARLES G. JANSKY.
